UNITED STATES PATENT OFFICE.

HARRY B. SMITH, OF NEW YORK, N. Y.

DESIGN FOR A BOX-BLANK.

SPECIFICATION forming part of Design No. 33,774, dated December 25, 1900.

Application filed June 12, 1900. Serial No. 20,082. Term of patent 14 years.

To all whom it may concern:

Be it known that I, HARRY B. SMITH, a citizen of the United States, residing at New York, (Brooklyn,) Kings county, State of New York, have invented and produced a new and original Design for Box-Blanks, of which the following is a specification.

My invention consists in a new and original design for box-blanks, and is illustrated in the accompanying drawings, in which—

Figure 1 is a plan view of a box-blank made according to my design. Fig. 2 is a longitudinal sectional view taken on the line xx of Fig. 1.

The leading feature of my design consists in a blank or body portion made substantially rectangular in plan view with each corner thereof cut away on a single curved line, said blank being provided with wings at each side and at each end, the maximum length of said side and end wings being slightly less than the maximum length and width, respectively, of the body portion of the blank.

Referring to the drawings, the reference-numeral 1 designates the body of the blank, which is made substantially rectangular in shape and having rounded corners 2, that are formed by cutting away each corner on a single curved line. The body of the blank is provided at each end with integral wings 3,

substantially oblong in shape, and the two sides of the body are provided with similar oblong wings 4. As shown in the drawings, the said side and end wings 3 and 4 are made integral with the body 1, but at the lines of connection between the said body and wings the blank is slightly cut or scored, as shown at 5 and 6. The wings 3 and 4 are of substantially the same width, and in length they are slightly shorter than the sides and ends, respectively, of the body portion of the blank between the lines of scoring, as shown, so that the lower or inner corners 7 of the said wings are separated or removed from each other. The opposite ends 8 and 9 of the side and end wings terminate in straight lines taken substantially parallel with the scorings 5 and 6, respectively, so as to form substantially angular openings at the four corners of the blank.

What I claim is—

The design for a box-blank substantially as shown and described.

In testimony whereof I have hereunto set my hand in presence of two subscribing witnesses.

HARRY B. SMITH.
